CLAIM

The ornamental design for an interchangeable support for a capillary electrophoresis cartridge cassette, as shown and described.

DESCRIPTION

FIG. 1 is a perspective view of a first embodiment of an interchangeable support for a capillary electrophoresis cartridge cassette;

FIG. 2 is a top view thereof;

FIG. 3 is a bottom view thereof;

FIG. 4 is a right side view thereof;

FIG. 5 is a side view thereof;

FIG. 6 is a perspective view of a second embodiment of an interchangeable support for a capillary electrophoresis cartridge cassette;

FIG. 7 is a top view thereof;

FIG. 8 is a bottom view thereof;

FIG. 9 is a right side view thereof;

FIG. 10 is a left side view thereof;

FIG. 11 is a perspective view of a third embodiment of an interchangeable support for a capillary electrophoresis cartridge cassette;

FIG. 12 is a top view thereof;

FIG. 13 is a right side view thereof; and,

FIG. 14 is a left side view thereof.

The broken lines in the drawings depict portions of the interchangeable support for a capillary electrophoresis cartridge cassette that form no part of the claimed design.
